UNITED STATES PATENT OFFICE

ROBERT GUY HUGGINS, OF TULSA, OKLAHOMA

AEROPLANE FRAME

Application filed April 11, 1931. Serial No. 529,439.

This invention relates generally to aeroplane frame construction and particularly to a new and novel aeroplane frame and method of composing and constructing the same, and 5 adapted to act as a foundation or skeleton for the aeroplane and to carry the units thereof in perfect and rigid alignment.

It is an object of this invention to provide an aeroplane construction of the type 10 described which will be constructed throughout of metal, the wing assembly being detachable from the fuselage assembly, so formed and constructed as to considerably reduce the cost of production of aeroplane 15 frame constructions, by simplifying not only the structure itself but the operations required in making and assembling the same.

It is also an object of this invention to provide pressed metal channel sections of the 20 type described in an aeroplane frame construction.

These and other objects of the invention, its nature, its composition and arrangement and combination of parts will be readily understood by any one acquainted with the art to which this invention relates upon consulting the following descriptions of the drawings, in which:

Figure 1 is a top plan view of my improved aeroplane frame partly broken away.

Figure 2 is a vertical transverse section looking in the direction of the arrows approximately on the line 2—2 of Figure 1.

Figure 3 is another transverse vertical cross sectional view looking in the direction of the arrows approximately on the line 3—3 of Figure 1.

Figure 4 is a side elevational view of Figure 1.

Figure 5 is a front elevational view taken from the left of Figure 1.

Figure 6 is an elevational view of one of the channelled members showing the manner of bracing the same.

Figure 7 is a longitudinal vertical sectional view taken through the fore part of the fuselage frame looking in the direction of the arrows approximately on the line 7—7 of Figure 1.

Figure 8 is a horizontal sectional view

taken approximately on the line 8—8 of Figure 4 looking in the direction of the arrows.

Figure 9 is a vertical longitudinal sectional view through Figure 6.

Figure 10 is a top plan view of Figure 6.

Referring in detail to the drawings, the numerals 5 refer generally to pressed metal side members or channel cross sections which make up the fuselage frame and are spaced and braced by suitable cross members 6, 7 and 8, the cross members being secured between the flanges of the channel shown particularly well in Figures 2 and 3, as well as in Figure 7. The cross member 7 is somewhat rearward of an intermediate point of the fuselage, and from this point the side members may converge as at 9 and 10, and they meet to form a point at 11 where they are attached to a vertical tail post 12 which rises above the side members 5 as seen in Figure 4. At the fore part of the fuselage, the side members 5 converge inwardly as at 13 and 14 just beyond or at their point of attachment to the front cross member 8. The forward ends 15 of these portions are spaced as shown at 15. A pair of parallel brace members 16 leads from the forward extremity of the portions 13 and 14 of the side members 5 and meet the cross member 8 and are rigidly attached thereto, preferably by welding or other suitable attaching means. It should be said that the cross members 6 and 7 are also preferably welded to the side members 5, as is the tail post 12. It will be noticed in the drawings that the channel members or side members 5 are suitably braced with adjustable cross rods 17 arranged in any suitable manner, and comprising the general type of adjustable brace rods illustrated in detail in Figures 6 and 9 wherein the flanges of the channel members are shown provided with countersunk angular bores or depressions 18 carrying an adjusting screw 19 adapted to draw upon a screw-threaded portion 20 on the free end of the cross brace rods 17. The other end of the brace rod is adapted to be attached by welding, riveting or other suitable means as at 21 through an opposing flange of the channel member. Throughout the drawings, the numeral 22 refers to

stamped or otherwise formed holes in the cross members designed to reduce the weight thereof.

Referring to the wing structure, it will be observed that it is composed of parallelly or otherwise spaced channel members 23 attached to the underside of the fuselage frame, in a detachable manner as seen in detail in Figures 2 and 3 as well as 7. Bolts or the like attaching means of a detachable character indicated at 24 are passed through the lower flanges of the fuselage side members 5 and through the upper flanges of the side members 23 of the wing assembly.

Similarly to the fuselage frame or assembly, the wing assembly is cross braced by similar brace rods 17, in order to lend rigidity and to equalize the stresses which it is to undergo. There is a difference, however, in the manner of placement of the wing assembly brace rods as seen in Figures 2 and 3. The manner of placing the brace rods in Figures 6 and 9 as well as 10 refers particularly to the fuselage frame or assembly. Referring to Figures 2 and 3 which are pertinent to the wing assembly, it will be seen that the brace rods 17a are at their end portions passed through the cross brace members 24 which space the side members 23 of the wing assembly.

The essence of this invention is comprised in the employment of channel section pressed metal members in the frame of an aeroplane, looking to superior rigidity, greater simplicity and a considerable reduction in production costs through reduction of amount of material used and operations involved, as compared to presently known structures of this general type.

Therefore, it will be definitely understood that I do not desire to limit the application of this invention to the particular modification set out herein to illustrate the principles thereof, and any change or changes may be made in material and structure consistent with the scope of the invention.

What is claimed is:—

1. An aeroplane frame construction of the type described employing a fuselage assembly composed of transversely spaced side members of pressed metal channel sections, and a detachable wing assembly similarly made, and longitudinally adjustable brace rods between each pair of said members, as well as rigid cross members.

2. An aeroplane frame construction of the type described employing a fuselage assembly composed of transversely spaced side members of pressed metal channel sections, and a detachable wing assembly similarly made, and longitudinally adjustable brace rods between each pair of said members and the members of the wing assembly, rigid cross members spacing the members of the fuselage and wing assemblies, and an engine

support comprising a forward extension of the fuselage assembly side members and parallel longitudinal brace members connected between the ends of said last mentioned side members and a forward one of said rigid cross members, said wing assembly being secured to the side members rearwardly of said engine support.

3. An aeroplane frame construction of the type described employing a fuselage assembly composed of a pair of transversely spaced side members of pressed metal channel sections and a detachable wing assembly similarly made, and adjustable brace rods between the pairs of said members composing the fuselage and wing assemblies, rigid cross members therebetween, said wing assembly being secured under said spaced side members of the fuselage.

4. An aeroplane frame construction of the type described employing a fuselage assembly composed of a pair of single transversely spaced side members in the form of pressed metal channels, and a detachable wing assembly similarly made, and adjustable brace rods between each pair of side and wing members, as well as rigid cross members for spacing the side members, said wing assembly being secured under said spaced side members of the fuselage, and the rear ends of the side members of the fuselage assembly being converged, and a tail post, attached at their point of meeting.

In testimony whereof I affix my signature.

ROBERT GUY HUGGINS.
